UNITED STATES PATENT OFFICE.

ROBERT GRUNDY BROOKE, OF MANCHESTER, ENGLAND, ASSIGNOR TO HOLDEN AND BROOKE LIMITED, OF MANCHESTER, ENGLAND.

INJECTOR.

Application filed July 22, 1927, Serial No. 207,731, and in Great Britain July 24, 1926.

This invention relates to injectors of the kind in which a sliding delivery cone is associated with and employed to control the injector overflow.

5 The object of the present invention is to provide, in a more effective manner than heretofore, for the prevention of movement of the delivery cone, whatever its function may be, except when purposely desired, and this I 10 effect by supply of steam. Thus premature overflow closing movement of the delivery cone, due to pressure set up in the delivery chamber by the steam jet previous to or during the formation of the working jet, can be 15 effectually prevented, whilst also keeping the overflow free and open whilst the injector is starting. Compared with the use of spring means for resisting such movement of the cone, the present method possesses the definite 20 advantage that the resistance to movement varies as the working pressure varies, just as is demanded if the action is to be reliable over the ordinary working range of an injector, so that there is obtained a true automatic ac- 25 tion over the whole of the range.

The invention is generally applicable and may be variously carried into effect. It may for example be applied to an injector embodying a combining cone having a sliding part 30 controlling an upper or supplementary overflow and particularly intended to work with hot feed water where it becomes necessary or desirable to close not only this supplementary overflow but also the ordinary overflow, and 35 an injector of this type has been chosen for illustration in the accompanying drawing, Fig. 1 of which is a longitudinal section of the parts essential to an understanding of the improvements. Fig. 2 is a similar view of 40 a portion of such an injector showing a modification.

In the said drawing 1 represents the body of the injector, 2 the water inlet, 3 the overflow branch, 4 the steam nozzle, 5 and 6 the 45 stationary and movable parts constituting the combining cone and 7 the delivery chamber. When an ordinary injector of this type, that is to say one having a stationary delivery cone, is at work the supplementary overflow 50 which takes place by way of the gap 8 and valve seating 8^a is closed and held closed by the action of the sliding part 6 of the combining cone itself, the ordinary overflow remaining open, but in the case of a sliding 55 delivery cone injector of this type, as illus-

trated, the delivery cone 9 closes the ordinary overflow at 10 and at the same time the outlet of the supplementary overflow at 8^a with it, so that it closes or controls both overflows.

The premature movement of the sliding de- 60 liver cone 9 may be prevented by forming or providing the said delivery cone with an enlarged part or piston 11 separating the delivery chamber 7 from another chamber 12 which is in communication through a passage 65 or passages 13, 14, 16 formed partly in the injector body, and, it may be, external piping, (not shown) with the same source of steam as that which works the injector, whereby the 70 sliding delivery cone 9 is held in position such that the overflow is open and free while the injector is starting. The pressure of the steam acting upon the enlarged part or piston 11 aforesaid need not be the same as that of the 75 steam which works the injector so long as it bears an approximately constant ratio thereto and it may, if preferred, be derived, for example, from some part in which there is a Venturi effect such as at the throat 15 of the 80 converging and diverging steam cone 4, or from a region near the throat in the converging or diverging part of such steam cone. When a predetermined delivery pressure is 85 reached the opposing pressure in the chamber 12 is overcome and the delivery cone is thereby moved to close the overflows. In the arrangements shown in the drawings the surface area subject to delivery pressure is larger than the piston area presented to steam in the chamber 12. In other words the area 90 90 acted upon by the delivery pressure is equal to that of the piston 11 plus that of an annulus corresponding to the cross section of the cone 9 at the point where it begins to widen out.

Any suitable form of packing or stuffing 95 box may be provided for the sliding delivery cone, 19 representing such a box and 20 being the gland thereof.

In some cases, the sliding portion 6 of the combining cone may be made in a number of pieces so as to form an additional overflow or overflows, as for example in exhaust steam injectors; or one or more additional permanently open overflows may be provided.

If desired the sliding cone 9 at the delivery chamber end may, as shown in Fig. 2, be provided with a rod or bar 21 passing to the outside of the injector through a suitably arranged stuffing box 22 and gland 23 so that in case of sticking, the sliding cone 9 can be 105 110

forcibly actuated by hand either by direct pull and push as through handle 24 or by any suitable lever or other mechanical arrangement.

5. The details may be variously modified.

By means of the present invention steam acting in the chamber 12 provides an ample margin of power to overcome both the pressure in the delivery chamber 7 and the friction of the packing around cone 9 while leaving the overflow unrestricted and free to act, and the closing of the overflow which takes place as soon as the delivery pressure overcomes the steam pressure in chamber 12, can be delayed as long as required, according to the ratio fixed between the area of the piston exposed to steam in chamber 12 and that of the surface subject to delivery pressure. The nearer these two areas approach one another 15 in the arrangement illustrated the higher will the pressure in the delivery chamber 7 have to become before the pressure in chamber 12 is overcome.

What I claim is:—

25. 1. A steam injector of the kind referred to, comprising a delivery chamber, a sliding delivery cone extending into said chamber, a chamber in communication with a source of steam and piston means connected to the sliding cone acted upon by the steam in such steam chamber, whereby movement of the cone is prevented, except when purposely desired, by pressure independent of that set up by the jet in the injector.

35. 2. A steam injector of the kind referred to, comprising a delivery chamber, a sliding delivery cone extending into said chamber, a chamber in communication with a source of steam, piston means connected to the sliding cone acted upon by the steam in such steam chamber, whereby movement of the cone is prevented, except when purposely de-

sired, by pressure independent of that set up by the jet in the injector and means whereby the cone can be forcibly actuated by hand. 45

3. In a steam injector of the kind referred to, a sliding delivery cone, a delivery chamber, a chamber through which the cone extends, which chamber is in communication with a source of steam, and a piston on the cone separating the delivery chamber from the steam chamber referred to.

4. In a steam injector of the kind referred to, a sliding delivery cone, a delivery chamber, a chamber through which the cone extends, which chamber is in communication with a source of steam, a piston on the cone separating the delivery chamber from the steam chamber referred to, a stuffing box forming part of the delivery chamber, a rod attached to the delivery cone and extending through the stuffing box to the outside of the injector and means whereby the rod can be pulled and pushed to forcibly move the delivery cone. 55

5. In combination, an injector body having main and supplementary overflows, a steam cone, an associated combining cone having a sliding part controlling the supplementary overflow, a delivery chamber, a sliding delivery cone extending into the delivery chamber and adapted to close the main overflow and move the sliding part of the combining cone to close the supplementary overflow, a piston chamber through which the delivery cone 75 passes, a piston on the said cone separating the delivery chamber from the piston chamber and steam connections placing the piston chamber in communication with the interior of the steam cone, for the purpose 80 specified.

Signed at Manchester, England, this seventh day of July, 1927.

ROBERT GRUNDY BROOKE.
